UNITED STATES PATENT OFFICE.

GEORGE WOLF, OF LOUISVILLE, KENTUCKY.

DESIGN FOR BADGE.

Specification forming part of Design No. **11,420**, dated September 16, 1879; application filed August 5, 1879.
[Term of patent 3½ years.]

To all whom it may concern:

Be it known that I, GEORGE WOLF, of Louisville, in the county of Jefferson and State of Kentucky, have invented a certain new Design for Badges or Pins; and I do hereby declare that the following is a full, clear, and exact description thereof, reference being had to the accompanying drawing, and to the letters of reference marked thereon, which form part of this specification.

My invention consists in a design for badges, scarf-pins, and similar articles, as will be hereinafter more fully set forth.

The annexed drawing fully illustrates my design.

The body A of the badge, pin, or similar article is made in somewhat oval form, containing a cross, B, the portions of the body below the side arms of the cross being made striped with alternate stripes of gold and red or other colors, as desired. In the center of the cross is the representation of a helmet, a.

Two swords, b b, cross each other under the center of the cross, so that the handles are above and the points below the side arms of the cross. Above the body of the article is the representation of a crown, C, containing the letters "C. K. of A."

What I claim is—

The design for badges, pins, and similar articles, consisting of the body A, with cross B, helmet a, swords b b, and crown C, with the letters "C. K. of A" thereon, substantially as shown and described.

In testimony that I claim the foregoing as my own I affix my signature in presence of two witnesses.

GEORGE WOLF.
